MACHINE FOR OPERATING UPON THE
HEEL-PORTIONS OF SHOESFrancis Low Brandt, Wakefield, Mass., assignor
to United Shoe Machinery Corporation, Paterson, N. J., a corporation of New Jersey

Application August 28, 1936, Serial No. 98,372

19 Claims. (Cl. 12—42)

This invention relates to machines for operating upon the heel-portions of shoes, it being especially directed to those which are employed in connection with the attachment of heels by fastenings driven from within the shoes. This machine may be utilized for performing the method of heel-attaching, with the production of the shoe, as disclosed and claimed in the application filed in my name in the United States Patent

10 Office on August 28, 1936, Serial No. 98,371.

Shoe-heels may be secured to the heel-seats of shoes in various ways. Different numbers of nails may be driven in groups along lines generally following the contour of the periphery of the heel-cup; to these there may be added or employed alone a central nail or other fastening inserted by the heelng machine; or such a fastening as a screw may be applied, either with or without the previous formation of a receiving opening. My invention has as an object the provision of a flexible and efficient apparatus by which such different heel-attaching operations may be performed fully or partially and without the application of excessive forces which might cause injury to the work or to the machine.

In the attainment of the above object, I combine with a jack or other shoe-support through the top of which open an inner passage and a set of outer passages, a compound plunger reciprocating in the support and operating drivers in the support-passages. The drivers in the outer passages preferably rise to the passage-openings, so they are adapted for the insertion of attaching nails with their heads sunk in the material of the heel-seat. The inner driver, which may be used alone if desired, has a portion which terminates its upward movement a substantial distance below the opening of its passage and is arranged to receive at its upper extremity different operating devices which furnish driver-terminals. These devices may consist of a head which is adapted to insert a driven fastening, or it may take the form of a punch by which an opening is produced in the heel-seat of a shoe and in a heel clamped upon the heel-seat by a pressure-abutment co-operating with the support. It will be evident that the drivers are capable of utilization in different groups, and that the size and character of the groups will alter the forces which must be applied to accomplish the desired result. These forces may be so great as to produce harmful effects. If the pressure upon the work is sufficient to hold the heel firmly upon the heel-seat to prevent the nails from being crippled and to insure a tight crease, the heel may be crushed, its

cover deformed or excessive strain thrown upon the machine. To avoid this difficulty, my compound driver-plunger has two independently movable portions carrying, respectively, the inner and outer drivers. Because of this independence, the plunger-portions may be reciprocated at different times in the operating cycle, and thus only a part of the total stress applied at any one time. This may be kept easily within safe limits. Herein are shown a tubular plunger-portion for the outer drivers reciprocating in the frame, this having reciprocating within it a plunger-portion for the inner driver. If a punch is to be used as the terminal device upon the inner driver, the inner plunger-portion is also tubular to allow the discharge of the waste. This waste may be received by a deflector and thus kept clear of the actuating mechanism. In the present instance, this actuating mechanism is furnished by a cam and a crank which may act respectively upon the outer and inner plunger-portions and are carried by a driving shaft. The angular relation of these two actuating elements will give the desired timing of the driver-groups in the operating cycle. Means is provided whereby the effect of the cam is transmitted, without interference, to an element of the machine.

A particular embodiment of the invention is illustrated in the accompanying drawings, in which

Fig. 1 is a partial, vertical, transverse section through the improved machine;

Fig. 2, a similar view in a plane at right-angles to Fig. 1;

Fig. 3, an enlarged, transverse section through the jack-top, showing a set of nails being inserted by the outer drivers, while the inner driver with its terminal-punch rests;

Fig. 4, a like view, with the inner driver raised;

Fig. 5, a view similar to Fig. 4 but with the inner driver carrying a head for the insertion of a tubular fastening, and

Fig. 6, a perspective view of such tubular fastening.

I have chosen to disclose my invention as applied to a commercial heel-attaching machine, which is the subject of Letters Patent of the United States No. 2,033,158, Standish, March 10, 1936. It is to be understood, however, that this is in no way essential but simply furnishes a convenient arrangement. Of this machine there appears a portion of the frame 10 having journaled in it a horizontal driving shaft 12 by which a driver-plunger P is reciprocated vertically in the frame. At the top of the frame a shoe-supporting

jack 14 is mounted, and co-operating with this jack is the usual heel-pressure-abutment 16 carried by side-rods 18, 18 guided in the frame at opposite sides of the jack. Fluid means (not illustrated) joins the plunger to the heel-abutment in such a manner that the pressure applied by the latter varies with the resistance encountered by the plunger during the driving stroke.

I form the plunger P in two parts, an outer portion 20, which is guided for vertical reciprocation in the frame and which is tubular, and an inner portion 22 reciprocating within the outer portion. Upon a sleeve 24 threaded into the upper extremity of the plunger 20 is separably carried a driver-plate 26, and into this plate is threaded for individual, vertical adjustment a set of outer drivers 28, each having a lock-nut 30. This set may be five in number. The inner plunger 22 is threaded at its upper end to receive an inner driver 32. When the drivers 28 of the outer set are in their raised position (Fig. 3), to which they are carried by the plunger 20, their upper ends, upon which the heads of the nails N to be inserted rest, lie approximately at the openings through the jack-top of passages 34 in which these drivers operate. The relation is preferably such that the nails are slightly sunk in the heel-seat-material. The driver 32 has a threaded end 36 which is substantially below the opening in the jack-top of an inner passage 38 in which it is reciprocated by the plunger-portion 22. This thread is to permit it to receive different terminal-portions. One of these end-portions may be, as appears in Figs. 1 to 4, inclusive, a tubular punch 42, and since such a punch is to be employed and will produce within it waste-pieces, the driver 32 is also preferably tubular, as is the plunger-portion 22. The punch is generally cylindrical and has at its upper extremity the customary cutting edge 44. It is shouldered at 46 to engage the end of the driver 32, either directly or through interposed washers 48 by which the depth of projection of the punch into the work is controlled. When thus adjusted, the punch in the raised position of its plunger (Fig. 4) enters the heel to be attached to the proper depth to receive an attaching screw. The diameter of the punch corresponds to that of the opening for the screw. Instead of a punch, the terminal-portion of the driver 32 may consist, as shown in Fig. 5, of a head 50 secured in place and adjusted in the same manner as the punch. The driver member 32, 50 is preferably of greater diameter than the drivers 28, being adapted to support and insert a relatively large fastening F. Such a fastening is illustrated in Figs. 5 and 6. It is tubular and has at one extremity a head h of greater diameter than the shank or body b and, at the opposite end, a reduced, penetrating edge e. To increase the retentive effect of the fastening F, it may be provided with a circumferential projection or projections extending along the shank from the edge e. Preferably, this portion is in the form of a continuous helix p.

In driving a considerable number of nails for the attachment of heels, or when the attaching operations include the driving into the work of a member of relatively large diameter, as the terminal-punch 42 of the driver 32 or the fastening F inserted by the head 50 of the driver 32, the clamping force exerted by the heel-abutment 16 must be considerable to prevent the upward thrust of the fastenings from displacing the heel. Were this to occur, the nails might not be driven properly, and there might result a gaping crease.

On the other hand, with adequate pressure to resist the thrust of the drivers, the heel may be crushed or its covering wrinkled. In any event, the strain upon the machine elements is heavy. I avoid such effects by dividing the driver-action 5 so it occurs during different periods in the operating cycle. Upon the driving shaft 12 is a cam consisting of spaced sections 60, 60. The shaft is also sectional, the cam-sections being carried by the adjacent, spaced ends of the shaft. Joining 10 the inner faces of the cam-sections is an eccentrically placed crank-pin 62. The outer and inner plungers have lower terminal-portions 64 and 66, respectively. The former portion is guided in the frame and is provided with spaced ends to 15 which may be attached wear-plates 68, 68 resting upon the cam-sections 60, 60. The plunger 20 with its drivers 28 are held down, with the wear-plates urged toward the cam, by an expansion-spring 70 surrounding the body of the plunger and 20 interposed between the terminal-portion 64 and the frame 10. The terminal-portion 66 of the inner plunger 22 is guided within its companion portion 64 and is joined by a connecting rod or link 72 to the crank-pin 62. The upper end of 25 the link comes directly beneath the passage in the plunger 22, which is alined with the passage in the driver 32, and in the punch 42 when the latter is in use. I prefer to furnish upon this end of 30 the link lateral extensions 74, 74 transversely hollowed to trough-shape. The relation of the crank-pin to the portion of the cam of maximum diameter may be such that they cause the extreme upward movements of the drivers 28 and 32, respectively, substantially 180° apart during the 35 rotation of the driving shaft 12. Therefore, while the drivers 28 are inserting a load of nails the driver 32 is resting, and conversely.

In the machine of the previously mentioned patent, a vertical rod herein designated as 76 40 and movably mounted in the frame, is normally raised by a spring 77 and is acted upon by the cam of the plunger-operating mechanism to control the valve mechanism of the apparatus. The sections 60, 60 of the cam spaced from each other 45 by the crank-pin 62 in the present apparatus, are carried out of vertical alinement with the rod. To render the sections effective to actuate the rod, there is pivoted upon the frame at one side of the rod an arm 78 which, at its inner end, is sufficiently wide to contact with both cam-sections at its upper face and at its lower face rests upon the rod. The cam-action is transmitted through the arm to the rod without the balance of the force applied being disturbed by the lateral 50 placement of the sections.

It will be assumed that in the use of the apparatus it is desired to insert a heel H to be attached to a shoe S supported by the jack 14, a load of nails N and in the same operating cycle 60 to produce a hole in the heel to receive a screw to be applied later. The punch 42 forms the terminal of the driver 32, and a load of nails will be supplied to the passages 34 resting upon the ends of the drivers 28. At this time, all of 65 said drivers are lowered, as appears in Figs. 1 and 2. With the shaft 12 rotating as indicated by the arrow in Fig. 1, the cam 60 will first elevate the portion 20 of the plunger P. The arm 78 is at the same time freed and the rod 76 70 raised by its spring 77 to cause the abutment 16 to press the heel upon the heel-seat of the shoe. The drivers 28 force the nails N through the heel-seat of the shoe into the heel. During this time, the crank-pin 62 is lowering the portion 75

22 of the plunger P with its driver-punch 32, 42. After the insertion of the nails N has been completed, the cam 60 allows the spring 70 to lower the plunger-portion 20, while the elevation of the plunger-portion 22 and the driver 32 begins under the influence of the crank-pin 62. The punch-terminal is driven through the heel-seat-material of the shoe into the heel to the extent necessary to produce a hole of the proper depth to facilitate the later insertion of a screw. When the crank-pin passes the center and begins to descend, the punch is lowered by the driver. The frictional force exerted upon the heel-substance within the punch is greater than the resistance offered by the connection between material surrounded by the punch and the body of the material. Said connection is therefore broken, and the descending punch removes the pill from the work to be ejected by the pressure upon it of succeeding pieces. These pieces fall through the passages in the driver 32 and plunger 22 upon the deflector 74 and are directed thereby from the machine. During this second portion of the operating cycle, the cam 60 frees the rod 76 to allow the abutment 16 to be elevated, and the shoe with its nailed heel and the formed screw-hole may be removed from the jack. Because of the separation of the operations into groups, the forces applied to the work and the burdens put upon the work-retaining and fastening-driving mechanisms are divided, and the danger of injury is minimized.

If a center fastening, such as the tubular device F, is to be driven, as well as the nails N, the punch 42 is unscrewed and the driver-head 58 substituted. The operation may be precisely as before, save that when the nails are supplied to the drivers 28, a fastening is also placed upon the driver-head. When the work has been positioned, and the machine started, the nails are inserted during the first portion of the operating cycle and the single large fastening during the second portion.

Having described my invention, what I claim as new and desire to secure by Letters Patent of the United States is:

1. In a machine for operating upon the heel-portions of shoes, a shoe-support having opening through the top a set of outer passages and an inner passage, a compound plunger comprising a plurality of elements and reciprocating in the support, a set of drivers operated by an element of the plunger in the outer passages and each upon elevation of the plunger rising to its passage-opening, and a driver-portion operated by another element of the plunger in the inner passage and terminating its upward movement a substantial distance below the opening of its passage, the inner driver-portion being arranged to receive at its upper extremity different operating devices.

2. In a machine for operating upon the heel-portions of shoes, a shoe-support having opening through the top a set of outer passages and an inner passage, a compound plunger reciprocating in the support and consisting of two independently movable portions, a set of drivers operated by one portion of the plunger in the outer passages and each upon elevation of the plunger rising to its passage-opening, and a driver-portion operated by the other portion of the plunger in the inner passage and terminating its upward movement a substantial distance below the opening of its passage, the inner driver-portion be-

ing arranged to receive at its upper extremity different operating devices.

3. In a machine for operating upon the heel-portions of shoes, a shoe-support having opening through the top a set of outer passages and an inner passage, a compound plunger comprising a plurality of elements and reciprocating in the support, a set of drivers operated by an element of the plunger in the outer passages and each upon elevation of the plunger rising to its passage-opening, and a driver operated by another element of the plunger in the inner passage and terminated by a tubular punch emerging through its passage-opening.

4. In a machine for operating upon the heel-portions of shoes, a shoe-support having opening through the top a set of outer passages and an inner passage, a compound plunger comprising a plurality of elements and reciprocating in the support, a set of drivers operated by an element of the plunger in the outer passages and each upon elevation of the plunger rising to its passage-opening, and a driver-portion operated by another element of the plunger in the inner passage and terminating its upward movement a substantial distance below the opening of its passage and having secured to it a head rising into substantially the same relation to its passage-opening as the outer drivers.

5. In a machine for operating upon the heel-portions of shoes, a shoe-support provided with a passage opening through its top, a pressure-abutment co-operating with the support to clamp a heel upon a supported shoe, a plunger reciprocating in the support, and a driver carried by the plunger and operating in the passage, said driver terminating in a tubular punch movable within the support-passage and discharging therethrough the pills produced.

6. In a machine for operating upon the heel-portions of shoes, a shoe-support having passages opening through the top, a plunger having portions reciprocating in the support and each movable independently of the other during action upon the work, and drivers movable by the plunger-portions in the passages.

7. In a machine for operating upon the heel-portions of shoes, a shoe-support provided with passages opening through its top, a plunger having independently movable portions reciprocating in the support, drivers movable by the plunger-portions in the passages, and means for reciprocating the plunger-portions in opposite directions during action upon the work.

8. In a machine for operating upon the heel-portions of shoes, a shoe-support having passages opening through its top, a plunger having independently movable portions reciprocating in the support, and drivers movable by the plunger-portions in the passages, one of said drivers and its plunger-portion being tubular.

9. In a machine for operating upon the heel-portions of shoes, a shoe-support having passages opening through its top, a plunger having independently movable portions reciprocating in the support, drivers movable by the plunger-portions in the passages, one of said drivers and its plunger-portion being tubular, and a deflector to which the passages through the tubular plunger and driver deliver.

10. In a machine for operating upon the heel-portions of shoes, a shoe-support having a passage, a plunger reciprocating in the support, means for reciprocating the plunger, a driver movable by the plunger in the passage, and a de-

flector to which the passage through the driver delivers, said deflector being carried by an element of the reciprocating means.

11. In a heel-attaching machine, a frame, a jack mounted thereon and provided with passages, an outer tubular plunger-portion reciprocating in the frame, an inner plunger-portion reciprocating within the outer portion, and drivers carried by both plunger-portions and being movable in the jack-passages.

12. In a heel-attaching machine, a frame, a jack mounted thereon and provided with passages, an outer tubular plunger-portion reciprocating in the frame, an inner plunger-portion reciprocating within the outer portion, drivers carried by both plunger-portions and being movable in the jack-passages, and means for actuating the plunger-portions to render the drivers of said portions effective at different times in an operating cycle.

13. In a heel-attaching machine, a frame, a jack mounted thereon and provided with passages, an outer tubular plunger-portion reciprocating in the frame, an inner tubular plunger-portion reciprocating within the outer portion, nail-drivers carried by the outer portion, and a tubular punch carried by the inner portion, the drivers and punch being movable in the jack-passages.

14. In a heel-attaching machine, a frame, a jack mounted thereon and provided with passages, two plunger-portions reciprocating in the frame and having drivers operating in the jack-passages, a shaft journaled in the frame, a cam upon the shaft acting upon one plunger-portion, and a crank-pin revoluble by the shaft and joined to the other plunger-portion.

15. In a heel-attaching machine, a frame, a jack mounted thereon and provided with passages, two plunger-portions reciprocating in the frame and having drivers operating in the jack-passages, a shaft journaled in the frame, a cam having sections spaced from each other upon the shaft, said sections contacting with one plunger-portion, a crank-pin connecting the cam-sections, and a link joining the crank-pin to the other plunger-portion.

16. In a heel-attaching machine, a frame, a jack mounted thereon and provided with passages, an outer tubular plunger-portion reciprocating in the frame and having spaced downward extensions, an inner plunger-portion recipro-

cating within the tubular portion and having a terminal lying between the extensions of the outer plunger-portion, the plunger-portions having drivers operating in the jack-passages, a shaft journaled in the frame, a cam having sections spaced from each other upon the shaft and contacting with the plunger-extensions, a crank-pin connecting the cam-sections, and a link joining the crank-pin to the terminal of the inner plunger-portion.

17. In a heel-attaching machine, a frame, a jack mounted thereon and provided with passages, an outer tubular plunger-portion reciprocating in the frame, an inner tubular plunger-portion reciprocating in the outer portion, the plunger-portions having drivers operating in the jack-passages, the driver of the inner portion terminating in a punch, a cam for contacting with the outer portion, a crank and link for actuating the inner portion, and a deflector for the waste produced by the punch, said deflector being carried by the link.

18. In a heel-attaching machine, a frame, a jack mounted thereon and provided with passages, two plunger-portions reciprocating in the frame and having drivers operating in the jack-passages, a shaft journaled in the frame, a cam having sections spaced from each other upon the shaft, said sections contacting with one plunger-portion, a crank-pin connecting the cam-sections, a link joining the crank-pin to the other plunger-portion, a member arranged to control an element of the machine and movable beneath the crank-pin, and a transmitting member resting upon the controlling member and actuated by the cam to move said controlling member.

19. In a heel-attaching machine, a frame, a jack mounted thereon and provided with passages, two plunger-portions reciprocating in the frame and having drivers operating in the jack-passages, a shaft journaled in the frame, a cam having sections spaced from each other upon the shaft, said sections contacting with one plunger-portion, a crank-pin connecting the cam-sections, a link joining the crank-pin to the other plunger-portion, a rod sliding in the frame beneath the crank-pin and arranged to control an element of the machine, and an arm pivoted upon the frame at one side of the rod and resting thereon and engaged by both cam-sections to actuate the rod.

FRANCIS LOW BRANDT.
